UNITED STATES PATENT OFFICE.

ERNEST E. WIESE, OF BRECKSVILLE, OHIO.

DESIGN FOR A LAMP.

Application filed March 24, 1927. Serial No. 21,311. Term of patent 3½ years.

To all whom it may concern:

Be it known that I, ERNEST E. WIESE, a citizen of the United States, and a resident of Brecksville, in the county of Cuyahoga and State of Ohio, have invented a new, original, and ornamental Design for a Lamp, of which the following is a specification.

Reference is had to the accompanying drawing which shows a perspective view of a lamp embodying my design.

I claim:

The ornamental design for a lamp, as shown.

ERNEST E. WIESE.
